DUMP BAILER

William E. Barnes, Beaumont, Tex., assignor to Sun Oil Company, Philadelphia, Pa., a corporation of New Jersey

Application May 10, 1956, Serial No. 583,968

5 Claims. (Cl. 166—162)

This invention relates, generally, to dump bailers for use in oil and other deep wells, and specifically to the valve operating mechanism of such devices which controls the release of the bailer contents.

Dump bailers, as distinct from similar devices used as sampling mechanisms operating in reverse order, are required to carry material into the well for purposes assisting in the production of petroleum at the earth's surface. The material so introduced is generally of an inhibiting nature to reduce corrosion of tubing and tools. Administration of such material from the earth's surface, although used as one means for treating wells, leaves doubts as to proper placement and effectiveness.

Similar devices presently used in this field have not satisfactorily solved these problems, and have raised additional questions. The matter of discharging the contents of the bailer positively and completely at a selected elevation, in the well or on bottom hole contact, requires controlled operation of the valve portion of the mechanism. A valve, normally positioned in the bailer bottom either as a separate section, or as part of the complete bailer, must be either closed or open in any stage of operation. A fluctuating operation of the valve mechanism will dispense the contents at improper elevations in the well, or shut off the flow before the charge has been administered.

It is the principal object of this invention to provide an improved dump bailer which will retain the contents until released by a valve mechanism, and then so operate the valve as to insure complete discharge of the contents.

Controlled use of the bailer contents in the well is closely associated with the preparation of the bailer to administer the charge. Measured filling of the bailer and the ease with which this is accomplished are to be considered. It is not always feasible to fill a bailer through a top opening as the size of such an opening may be restricted because of special usage. Where the device is used in a well with well fluids covering the areas to be treated, it is necessary to reduce the bailer top opening to vents which assist the flow of the liquid contents from the bailer by admitting balancing pressures yet prevents displacement of treating liquids by inrushing well fluids. In this type of bailer, having restricted top openings, filling with measured quantities of liquid becomes a major problem.

It is, therefore, a further object of this invention to provide an improved dump bailer for general use which is easily filled with the selected liquid contents in proper measured amounts without dismantling the device.

And yet a further object of this invention is to provide a dump bailer bottom for use with any conventional bailer body through which the above cited objects of controlled operation in both emptying and filling are obtained.

In carrying out these and other objects evident as the description proceeds, the invention is described in the accompanying specification in reference to the accompanying drawing, in which:

2

Figure 1 is an elevational view partly in section showing the complete device together with a filling means attached.

Figure 2 is an enlarged sectional view through the bailer bottom and the lower end of the bailer charge chamber showing the valve mechanism in the open position.

The dump bailer of the invention is illustrated in the accompanying drawing where a conventional bailer is indicated with a modified top and bottom designed to meet the objects of this invention as described. A top closure 10, apertured as at 12 to communicate with the interior chamber 13 of the bailer 14, forms a wire line connector by means of a top aperture 16. Such a connection is suggested in Figure 1 as a threaded thimble apertured to pass the wire line through the closed end and forming a keeper for an enlarged end of the line which usually takes the form of a lump of metal or a knot in the line. As is evident this top closure 10 takes the place of a bail or like handle device normally attached to an open container like a bucket, and adapts the conventional bailer for use in liquid filled wells.

To the bottom of the bailer 14, a plug 18, apertured longitudinally at 20 to receive slidably tubular valve member 22, is connected. The valve seat 24 is formed by counterboring the upper portion of aperture 20 to receive the flanged end of valve member 22. An O ring 26 peripherally engages the flanged end of the valve member 22 for sealing contact with valve seat 24, thus completing valve head 21. Apertures 27 radially extend from the valve seat counterbore 24 to the external periphery of the plug 18 for discharge of the liquid contents of the bailer 14 during operation.

As the valve member 22 is fashioned from tubular material, the aperture 28 through the length of the valve member forms a passage connecting the bailer chamber 13 with the exterior through the valve. To seal the chamber and keep the liquid contents carried therein from escaping through the valve opening, a pressure responsive closure 32, shown here as a ball 34 with resilient pressure means or spring 36, closes the aperture 28. A split ring 37 against which spring 36 abuts, expands to fit into a peripheral groove to position the spring in compression as indicated in Figure 2. This internal sealing means, as distinguished from the external sealing means described as O ring 26, may be placed anywhere in the length of the tubular valve member and may assume any form of check valve arrangement well known in the art.

At the bottom of the tubular valve means which extends through the plug 18, a lower flanged portion 38 limits the distance of travel relative to the plug 18 when moving upwardly to release the contents of bailer chamber 13 as later described, and also furnishes sufficient body to connect means for the filling operation. Shown as a part of Figure 1, a source of treating liquid 40 is indicated connected to a pumping means 42 by which a supply is forced through hose 44. A connector 46 is threaded to engage flange 38 of the tubular valve member 22 forming the supply path of the treating liquid from source 40 to chamber 13 of bailer 14.

Once the charge of liquid is transferred to the bailer, the hose connector 46 is disengaged. A plug 50 is shown in Figure 2 as threaded into flange 38 to keep the internal threaded portion of the flange free of dirt to readily receive the hose connector 46. By means of the external seal 26 engaging valve seat 24, and the internal sealing means 32 seated by force of the liquid in chamber 13 and spring 36 forcing ball 34 into the closed position, chamber 13 is sealed ready for lowering into the well to be treated. This position of sealed relation is shown in Figure 1.

In both Figures 1 and 2, referred to above for description of other elements of the combination, means for positively holding the valve member 22 in both closed and open positions relative to the plug 18 is shown. Latch means shown as detent 52 comprising a ball 54 with shoulder portion 55 for guiding and support purposes, pressed continuously by spring 56 into a groove 58 in the shank portion of tubular valve member 22 at a selected position between upper and lower flange 21 and 38 respectively, holds the valve in closed position (Fig. 1). As shown, this latching means is set into plug 18 through hole 60 drilled to receive it, and tapped for a set screw 62 at the outer plug surface. This set screw can be advanced or withdrawn to increase or decrease the pressure of spring 56 as required for proper action.

Reference to Figure 2 in which the valve is open, and held in that position by the elements described, will be easily understood. The valve is lifted by contact with the well bottom and is urged beyond the restraint of the latch means 52, and slides into locking engagement in the second or lower groove 64. On reaching this engagement the latch holds the valve member in the open position to discharge the bailer contents as explained in the operation of the device which follows.

The operation of the device, to those versed in the art, will be evident from the figures of the drawing and the detailed description of the elements given above, without further discussion. However, to clarify any questions relative to cooperation of the several elements and to emphasize the improvement in the art as embodied in this device, a description of operation will be given.

Preparation of the device for operation is indicated in Figure 1. By grasping the lower flange 38 of the tubular valve member 22 and pulling it downwardly as far as it will go, the valve head 21 is seated in the seat portion 24 of plug 18 with the O ring sealably engaging the same. The latch engages the upper groove, locking the valve in closed position. With the bailer held in vertical position as by the wire line suspended in the derrick structure (not shown), the liquid charge source is connected as shown in Figure 1 and the desired amount of liquid is forced into the bailer chamber 13. The pressure responsive sealing means 32 passes the liquid and closes in internal sealing engagement with the aperture shoulders, as shown, when the pressure is removed. Once charged with liquid, the hose is disconnected, and the plug 50, if desired, is inserted to close the valve aperture 28 and act as a striker to operate the device. The bailer is then lowered into the well.

Contact of valve member 22 with the bottom of the well moves the valve member upward relative to the plug 18, depressing the spring pressed latch means as the upper groove slides over the ball 54. It will be understood that the force on the valve required to release the contents of the bailer is required to be great enough to overcome both the restraining effect of the latch and the pressure of the liquid on the valve. Accidental bumping on the side of the well, liquid or gas pressure contacted during the descent, will not be of sufficient force to open the valve.

Under action of contact with the bottom of the well, the valve member moves upwardly until the latch moves into the second, or lower, groove on the valve member where it engages, holding the valve open. The space between the grooves is substantially the distance 35 the lower flange extends beyond the bottom of the plug. In this way the action of unlatching and latching is made certain and no possibility of the valve member sliding beyond the latched open position is allowed.

With the valve held in the open position by the spring-pressed ball engaging the lower groove 64, the liquid contents of the bailer pass downwardly around the valve head 21 into the enlarged valve seat aperture and escape from the bailer through the apertures 27. The valve is held in the open position until re-set in the closed posi-

tion as described at the beginning of the description of operation. By admitting pressure above the liquid charge in the bailer body through apertures 12 provided in the wire line connection on the top of the bailer, the liquid charge is caused to flow freely from the chamber. This is true in either liquid or gas-filled wells, or in dry holes, where air will displace the charge through apertures 12.

I claim:

1. A dump bailer bottom comprising a longitudinally apertured plug having means for connection with a bailer, a valve seat in the aperture of said plug transversely apertured to release the dump bailer contents, a slideable valve member in the plug aperture positioned to sealably engage the valve seat and extend through the plug, said valve member being longitudinally apertured to form a passageway therethrough, a pressure responsive valve means in said passageway, and latch means in the plug engageable with the slideable valve member in closed and open positions.
2. A dump bailer bottom comprising a longitudinally apertured plug having means for connection with a bailer and having a transversely apertured valve seat therein, tubular valve means longitudinally slideable in said apertured plug and extending therethrough, seal means externally of the tubular valve means operably engaging the valve seat of the plug in the closed position, pressure responsive sealing means normally closing the internal opening in the tubular valve means, spring pressed latching means releasably engaging the tubular valve means in closed and open positions, and means to receive fluid for filling the bailer through the projecting portion of the tubular valve means.
3. A dump bailer bottom comprising a longitudinally apertured plug having means for connection with a bailer, a valve seat formed in the longitudinal aperture and radially apertured to vent the bailer, a tubular valve member extending through the plug and longitudinally slideable in the plug aperture being adapted to sealably engage the valve seat at the upper end thereof, resilient closing means inside the tubular valve member responsive to pressures, spring pressed latching means in said plug releasably engaging the tubular valve member holding said member in closed and open positions relative to the valve seat, and means in the projecting end of said tubular valve member to receive fluid to fill the bailer.
4. A dump bailer for use in well holes comprising a tubular body having means for connection with a wire line on the top and a valve means on the bottom, said valve means including a longitudinally apertured plug having a valve seat in said aperture at the tubular body engaging end with radially extending apertures to vent the tubular body, a tubular valve member extending through the longitudinally apertured plug and slideable relative thereto, sealing means externally mounted on the tubular valve member to operably engage the valve seat, internal pressure responsive sealing means normally closing the passage in the tubular valve member, spring-pressed latching means positioned in said plug to operably engage the tubular valve member in either the open or closed position relative to said valve seat, and means to receive fluid through the tubular valve member to fill the bailer.
5. A dumping bailer adapted to carry treating material into well boreholes comprising an elongate body providing an interior chamber to carry said treating material, a wire line connector fastened to the top of the body having apertures therethrough to transmit well pressure to the interior chamber, a bottom closure on said body longitudinally apertured for the passage of the treating material, a tubular valve member extending through the longitudinal aperture of the bottom closure and slideable relative thereto, a seal ring on the valve member positioned to sealably engage the bottom closure aperture externally of the tubular valve member, spring pressed closure means internally sealing the tubular valve member, spring

pressed latching means in the bottom closure releasably engaging the tubular valve member in the open or closed position relative to the interior chamber, and connecting means on the portion of the tubular valve projecting from the bottom closure adapted to receive treating material 5 for transmission through the valve to the chamber.
